UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

APPARATUS FOR THE AUTOMATIC REGULATION OF THE HYDRAULIC BRAKES OF GUNS.

1,333,282.

Specification of Letters Patent.

Patented Mar. 9, 1920.

Application filed March 31, 1919. Serial No. 286,491.

To all whom it may concern:

Be it known that I, EUGÈNE SCHNEIDER, a citizen of the French Republic, and a resident of 42 Rue d'Anjou, Paris, France, have **5** invented a new and useful Improved Apparatus for the Automatic Regulation of the Hydraulic Brakes of Guns, which invention is fully set forth in the following specification.

10 This invention consists in improvements in that type of hydraulic brakes for guns, that comprises in the known manner a brake piston having a hollow piston rod attached to the fixed part or to the recoiling part, and **15** adapted to move in a cylinder and also along a counter-rod of peculiar profile, both of which are carried inversely by the recoiling part or by the fixed part.

The improvements consist in an apparatus **20** designed to allow of the length of the recoil to be maintained perfectly constant irrespectively of the elevation of the gun barrel in firing. The maintenance of this constant length obviates the draw-back of an increase **25** in the recoil at high elevations, which increase entails the necessity of a corresponding elevation of the height of the line of fire; this said elevation being of itself prejudicial to the stability of the gun.

30 According to this invention the maintenance of a constant length of the recoil at different elevations of the gun barrel is assured by an automatic adjustment of the initial position of the throttling member or **35** diaphragm relatively to the counter-rod of peculiar profile. For this purpose the throttling member is made capable of longitudinal movement in the piston, this movement taking place automatically and in proportion **40** to the elevation of the gun barrel, by reason of a connection being established between it and the elevating mechanism, or simply between it and the elevation movements of the gun barrel.

45 A practical embodiment of the invention is illustrated by way of example in the accompanying drawings in which:—

Figure 1 is a side elevation of a gun of **50** which the brake comprising the present improvements, is shown partly in longitudinal section.

Fig. 2 is a detail longitudinal section of the brake drawn to a larger scale.

Fig. 3 is a section on the line III—III of **55** Fig. 2.

Fig. 4 is a section drawn to a larger scale on the line IV—IV of Fig. 1.

In the illustrated example it is assumed that the brake cylinder A is fixed to the recoiling part, that is to say, the gun slide **60** B and the gun barrel C; it has fixed to its rear end *a* the counter-rod D of peculiar profile which is fitted at its free end with the usual valve D¹ of the device for moderating the running out of the gun again into **65** the firing position. The brake piston E¹ which is movable in the cylinder A and encloses in its cavity the counter-rod D, is attached by the end *e* of its rod E to a fixed part of the gun, such as for instance the **70** gun cradle F.

In the recoil, the braking is produced in the known manner by the throttling of the passage of the liquid from the front to the back of the cylinder A through the annular **75** space left between the throttling member or diaphragm G and the outer surface of the peculiarly profiled counter-rod D.

According to the present invention the throttling member G is capable of longitudinal **80** movements in the piston E¹ which are produced automatically in dependence on the mechanism for elevating the gun barrel C.

In the example shown the piston E¹ is **85** screwthreaded internally so as to constitute a nut for an external screwthread on the throttling member G. The longitudinal displacement of the throttling member in the piston is due to a rotational movement of **90** the piston rod E derived from the elevation movement of the gun barrel, and also to the guidance of the throttling member G on the counter-rod D. For this purpose the throttling member G is formed with two tenons **95** *g* engaged in grooves *d* in the counter-rod. The rotation of the piston rod E proportionately to the elevation of the gun barrel is effected as follows:—

A pinion H fixed on an extension of the **100** piston rod E, gears with a toothed wheel I fixed on a shaft J journaled in bearings *j* formed on the cradle F. A bevel pinion K fixed on the said shaft J, is driven by a bevel wheel L fixed on a shaft M that is journaled **105** in a bracket *f* attached to the cradle F. The bevel wheel L is attached to a pinion L¹ that gears with a toothed sector N provided on the gun carriage frame O.

Owing to the above described gearing **110**

every angular displacement of the gun barrel C produces a rotational movement of the piston rod E, and consequently a longitudinal displacement of the screwthreaded 5 throttling member G in the internal screw-thread in the piston E¹.

If the throttling member G is situated in the position shown in full lines in Fig. 2 when the gun barrel is horizontal, it will be 10 moved gradually from this position into the position indicated in dot and dash lines, according, as the gun barrel receives an increasing positive elevation, until the maximum elevation is reached. By this means 15 the bore of the throttling member G is moved into varying initial positions in front of the increasing cross sections of the counter-rod D.

In proportion as the elevation increases 20 the throttling of the passage of the liquid at the commencement of the recoil will be increased in its turn, and in this manner the forces will be counteracted that tend to increase the length of the recoil according to 25 the elevation of the gun barrel.

Besides the hereinbefore stated advantage, the maintenance of a constant length of the recoil is also of special value in its application to guns such as the gun illustrated in 30 Fig. 1, where the breech block separates from the gun barrel and engages the cradle at the end of the recoil for the purpose of acting as a rammer when it is run in again into the firing position.

35 What I claim is:—

1. In a fluid-pressure brake for guns, throttling mechanism comprising a cylinder and a coacting piston, said piston having an axial bore and an apertured wall for the 40 passage of the braking fluid from one side of the piston to the other during the relative movement of the cylinder and piston, a profiled counter-rod fixed to the cylinder and extending through the axial bore of the piston, a diaphragm screw-threaded in the axial bore of the piston and having a central opening registering with the counter-rod to throttle the fluid passing through the axial bore of the piston, said diaphragm having 45 a sliding engagement with the counter-rod to be held thereby against rotation, and means on the projecting end of the tubular rod to rotate the same together with the piston carried thereby, the turning of the piston operating through its screw-threaded engagement with the diaphragm to move the latter longitudinally of the axial bore in the piston to vary the initial throttling position of the counter-rod in the central opening of the diaphragm.

50 2. In a fluid-pressure brake for guns, throttling mechanism comprising a cylinder and a coacting piston, said piston having an axial bore and an apertured wall for the 55 passage of the braking fluid from one side of the piston to the other during the relative movement of the cylinder and piston, a profiled counter-rod fixed to the cylinder and extending through the axial bore of the

piston, a diaphragm screw-threaded in the axial bore of the piston and having a central opening registering with the counter-rod to throttle the fluid passing through the axial bore, means for holding the diaphragm 70 against rotation when the piston is turned so that the rotation of the piston will displace the diaphragm in the axial bore, and mechanism actuated by changing the elevation of the gun for rotating the piston to 75 displace the diaphragm in the axial bore to vary the initial throttling position of the counter-rod in the central opening of the diaphragm, the variation in the throttling opening being such that the initial throttling 80 is at its minimum with the gun in a horizontal position and increases to its maximum at the extreme elevation of the gun.

3. In a fluid-pressure brake for guns, a cylinder fixed to the recoiling member of a gun-carriage, a piston coacting with the cylinder having an apertured wall and an axial bore for the passage of the braking fluid from one side of the piston to the other as the cylinder moves on said piston, a rotatable 90 tubular rod fast at its rear end to the piston and projecting at its forward end beyond the cylinder with its projecting end held against longitudinal movement by engagement with the non-recoilable member of the gun-carriage, said rod having its tubular space communicating with the interior of the cylinder, a profiled counter-rod fixed to the rear end of the cylinder and extending through the axial bore of the piston into the tubular rod, 100 a diaphragm screw-threaded into the axial bore of the piston and having a central opening registering with the counter-rod to throttle the fluid passing through the axial bore of the piston, said diaphragm having 105 a sliding engagement with the counter-rod to be held thereby against rotation, and means on the projecting end of the tubular rod to rotate the same together with the piston carried thereby, the turning of the piston operating through its screw-threaded engagement with the diaphragm to move the latter longitudinally of the axial bore in the piston to vary the initial throttling position of the counter-rod in the central opening of 110 the diaphragm.

4. In a fluid-pressure brake for guns, a cylinder fixed to the recoiling member of a gun-carriage, a piston coacting with the cylinder having an apertured wall and an axial bore for the passage of the braking fluid from one side of the piston to the other as the cylinder moves on said piston, a rotatable tubular rod fast at its rear end to the piston and projecting at its forward end 120 beyond the cylinder with its projecting end held against longitudinal movement by engagement with the non-recoilable member of the gun-carriage, said rod having its tubular space communicating with the interior 125 of the cylinder to vary the initial throttling position of the counter-rod in the central opening of the diaphragm.

of the cylinder, a profiled counter-rod fixed to the rear end of the cylinder and extending through the axial bore of the piston into the tubular rod, a diaphragm screw-threaded 5 into the axial bore of the piston and having a central opening registering with the counter-rod to throttle the fluid passing through the axial bore of the piston, said diaphragm having a sliding engagement 10 with the counter-rod to be held thereby against rotation, a pinion fixed on the end of the tubular rod projecting beyond the cylinder, a toothed sector on the frame of the gun-carriage meshing with a pinion on 15 the non-recoilable member of the gun-carriage, and a gear-drive connecting said pinion so that the oscillation of the gun-car-

riage through the intervening mechanism will rotate the tubular rod and the piston carried thereby, the turning of the piston 20 operating through its screw-threaded engagement with the diaphragm to move the latter longitudinally of the axial bore in the piston to vary the initial throttling position of the counter-rod in the central opening of 25 the diaphragm, the timing of the variation being such that the initial throttling is at its minimum with the gun in a horizontal position and increases to its maximum at the extreme elevation of the gun. 30

In testimony whereof I have signed this specification.

EUGÈNE SCHNEIDER.
